A technical drawing of a curved metal component, likely a part of a lock mechanism. The component is U-shaped with a central vertical slot and two horizontal arms. It is labeled with the number '42' at the top, '48' on the left, '50' on the bottom left, and '42' on the bottom right. To the right of the component, the text 'Fig. 13.' is written in a cursive script.

INVENTOR
Archibald Wright

UNITED STATES PATENT OFFICE

2,327,688

MANUFACTURE OF UMBRELLAS

Arthur Wright, Forest Hills, N. Y.

Application May 28, 1940, Serial No. 337,570

9 Claims. (Cl. 135—31)

My invention relates particularly to means and method for the manufacture of self-rolling umbrellas, such as contained in my patent upon Self-rolling umbrella and process of producing the same, No. 2,167,860, granted August 1, 1939.

The object of my invention is to provide means and method whereby umbrellas of the above character may be readily and effectively manufactured. One of the objects is to provide a simple way of attaching springs to the tips of the ribs of an umbrella. Another object is to provide an effective and simple way of winding up the springs on the ribs. Another object is to provide a key by which the springs can be wound up or tightened, as desired. A further object is to provide a cover for the umbrella which will permit the springs to fully wind up the folds of the cover on the ribs. Another object is to prepare the springs in such a form as to enable them to be readily wound up on the ribs. Further objects of my invention will appear from the detailed description of the same hereinafter.

While my invention is capable of embodiment in many different forms by way of illustration I have shown only certain forms thereof in the accompanying drawing, in which—

Fig. 1 is a plan view of a portion of an umbrella showing a rib having a spring thereon for winding up the fabric on the rib, similar to Fig. 6 of my patent aforesaid;

Fig. 2 is a similar view showing a spring on the rib in the unwound or untightened position, having applied thereto a key in the preferred form preparatory to winding up the same;

Fig. 3 is a plan view of one form of key which can be used for winding up the ribs;

Fig. 4 is a right end view of the same;

Fig. 5 is a plan view of another form of key which can be used for the same purpose;

Fig. 6 is a left end view of the same;

Fig. 7 is a plan view of another form of key in two pieces for this purpose;

Fig. 8 is an end view of one of said pieces;

Fig. 9 is an end view of the other piece thereof;

Fig. 10 is a plan view of the preferred form of key which is the same as shown in Fig. 2;

Fig. 11 is an end view at one end thereof;

Fig. 12 is a right end view of the other end thereof;

Fig. 13 is a transverse section of said key; and

Fig. 14 is an end elevation of the spring in the form in which it is placed over the rib.

In the drawing I have shown an umbrella rib 1 of the usual U-shaped cross-section, which has the usual end 2 bent together and having a hole

3 through which the fastening means is applied to the usual ring 4 going over a stick 5 of the umbrella. Said umbrella may have any number of ribs, as for example eight, ten, twelve or sixteen. 5 Each of the ribs has the usual link 6 secured to it by a pivot pin 7. The links 6 are secured to the usual slide ring on the stick 5, which latter has the usual catch for holding said ring in position when the umbrella is down, the said ring and catch not being shown as it is of any usual construction. The umbrella has a cover 8 of any desired material, such as a woven fabric. The cover 8 is constructed in the usual way, that is to say so as to be comprised of sections 9 to fit between adjacent ribs when the umbrella is in the up-position, the sections 9 being stitched together along lines 10 of the ribs. However, the dimensions of the fabric sections 9 are different from the usual umbrella construction in that the 10 distance from the stick 5 to the end of the rib is made somewhat longer in order to allow for the shortening of the cover along the ribs when wound up thereon. The number of windings of the fabric on the ribs may be of any desired number to roll up completely the intervening portions of the fabric on the adjacent ribs, as hereinafter described. In ordinary types of umbrellas the number of turns of the fabric may, for example, by anywhere from two to six windings, and according to the number of windings the fabric is given the extra length along the direction of the rib as compared with the length of the rib and as compared with the length of the fabric in the ordinary umbrella construction. In other words the length that is added to this dimension of the fabric would be approximately or a little more than the number of windings of the fabric around the rib times the circular distance around the rib plus the normal length 15 of the fabric in the usual umbrella which is not self-rolling. On the end of each of the ribs 1 I have provided a tip 11 having a rounded head 12 and a cylindrical portion 13 provided with a bore 14 to fit over a substantially cylindrical constricted portion 15 on the outer end of the rib 1. The tip 11 has a hole 16 for threads 17, by means of which the tip is sewed to the fabric 9. The tip 11 is customarily sewed in this way while the cylindrical portion 13 faces outwardly away from the rib 2 and is then turned 180° preparatory to placing it over the rib 1. Before placing it over the rib 1, however, a helical spring 18, having a plain cylindrical end 19, is wound onto the cylindrical portion 13 of the tip, the spring 18 being 20 large enough to be thus forced over the end of

the tip by rotating thereon, but tight enough to remain securely in place once it has been forced over the end of the tip. The other end of the spring 18 has two spaced coils 20 and 21 and ends in a small hook 22 having a length of about half the diameter of the spring 18, and which leaves a recess 23 in the hook slightly larger than the thickness of the wall of the rib 1. The tip 11, having the spring 18 attached thereto in this way, is then slid over the end of the rib 1 so that the hook 22 overlies one edge of the rib 1. Any one of the several different types of keys illustrated in the drawing can then be applied to the rib for winding up the spring 18 thereon. The simplest form of key for this purpose is shown in Figs. 3 and 4, which comprises a nearly cylindrical but slightly coiled tube 24 having an inclined end 25 providing a point 26, to the rear of which there is located a notch 27 to be inserted along the outside wall of the rib 1 beneath the hook 22, that is to say in the recess 23, when the spring is being wound up initially from its unwound position. The spring 18 can now be given any desired number of turns. It will be noted that the form of the key 24 provides a slot 28 permitting the key to be inserted over the wall of the rib so as to encircle the latter and that upon rotating the key 24 to wind up the spring the fact that the two edges of the key adjacent to the slot 28 are not in the same circle will prevent these edges from catching on the edges of the rib. In case the spring has already received a number of windings, but it is desired to add further turns thereto, it is more convenient to insert the point 26 under the second coil 20 overlying the channel in the rib 1 and then to turn the key 24 until the notch 27 catches on the hook 22. Any desired number of turns may now be given to the spring. If, for example, the spring is of light stainless steel .018" in diameter, it will generally be given at least four more turns than in the number of windings mentioned above, which the fabric takes in winding up completely between the ribs. These windings of the spring 18 can readily be made, also, because the smallness of the hook 26 permits it to be moved around the periphery of the rib 1 without catching thereon. The key 24 can now be removed by withdrawing the notch 27 longitudinally out of the hook 22 and the key 24 can be removed from the rib 1 by rotating it in the reverse direction and thus removing it laterally from said rib. In Fig. 5 there is illustrated another form of key 29 made and operated in the same way as the key 24 except that there is a distinct spiral therein so as to produce overlapping edges 30 and 31. In the form of key shown in Figs. 7 and 8 there is a cylindrical part 32 having a longitudinal slit 33 permitting the same to be inserted over the rib 1. The diameter of the key 32 internally is somewhat larger than the diameter of the spring 18 as it is, in winding up said spring, positioned to rotate on top of the same. This key has another part 34 having a longitudinal slit 35 and a pushing flange 36 of such a diameter as to readily rotate on the rib 1 but so as to fit in one end of the cylindrical part 32 with the slit 35 diametrically opposite to the slit 33. The part 34 can be readily placed over the rib 1 and then inserted in the part 32. The part 32 has an F-shaped slot 37 having an inclined edge 38 to produce a point 39 like the point 36, and a notch 40 like the notch 27 so that said point 39 can be inserted, as before described, beneath the hook 22. The preferred form of key is shown in Figs. 10 to 14,

which combines the features of the construction in the keys 29 and 32. This key 41 has a rear end 42 similar in the cross-section to the key 29, and a cylindrical forward end 43 like the forward end of the part 32 so as to receive loosely within the same the spring 18. There is also a rectangular opening 44 in which there projects to a point below the internal periphery of the key 41 a point 45 adjacent to a notch 46 located on a bar 47 pivoted in ears 48 and 49 bent up from the body of the key 41, said bar 47 having a transversely curved thumb-piece 50 spaced at its center from the key 41 but fitting along the sides thereof, so that when the hook 22 of the spring is engaged in the notch 46, the thumb-piece 50 can be pressed downwardly so that the hook 22 just clears the rib 1 when the key 41 is being rotated to wind up the spring. The thumb-piece 50 is released when the spring is wound up to allow the hook 22 to engage the side of the rib 1. The use of this key is carried out in substantially the same way as the keys previously described except that in this instance one end of the key rotates on top of the spring 18 to permit easy winding of the spring and the other end rotates on the rib, eliminating the necessity of an additional supporting part for the key.

While I have described my invention above in detail I wish it to be understood that many changes may be made therein without departing from the spirit of the same.

I claim:

1. A self-rolling umbrella comprising a rib, a tip rotatable thereon having a cylindrical periphery and a coil spring on the rib tightly carried around said periphery.
2. A self-rolling umbrella comprising a rib, a tip rotatable thereon having a cylindrical periphery and a cylindrical spring on the rib tightly carried around said periphery.
3. A self-rolling umbrella having a rib, a tip rotatable thereon, and an umbrella cover secured to said tip and having a length along the rib greater than the distance between the points of attachment of the fabric to the umbrella in the direction of said rib.
4. A self-rolling umbrella having a rib, a tip rotatable thereon, and an umbrella cover secured to said tip and having a length along the rib greater, by at least the number of windings on the rib times the circumference of the rib, than the distance between the points of attachment of the fabric to the umbrella in the direction of said rib.
5. A self-rolling umbrella comprising a rib, a tip rotatable thereon, and a coil spring attached to said tip having a hook on the end of the spring substantially the length of the radius of the rib and located approximately adjacent the wall of the rib, adapted to be wound around the periphery of said rib.
6. A self-rolling umbrella comprising a rib, a tip rotatable thereon, and a coil spring attached to said tip having a hook on the end of the spring substantially the length of the radius of the rib and located approximately adjacent the wall of the rib, adapted to be wound around the periphery of said rib, the coil, of which the hook forms a part, as well as the adjacent coil being spaced away from the remainder of the spring.
7. The method of manufacturing self-rolling umbrellas which comprises applying to an umbrella a cover longer in the direction of the rib than the distance between the points in the umbrella to which the cover is attached; securing a

tip to the cover, applying a helical spring over the tip, placing the spring and tip over a rib on which the tip is rotatable, and winding up the spring on the rib.

8. The method of manufacturing self-rolling umbrellas which comprises applying to an umbrella a cover longer in the direction of the rib than the distance between the points in the umbrella to which the cover is attached, securing a tip to the cover, applying a helical spring over the tip, placing the spring and tip over a rib on which the tip is rotatable, and winding up the spring on the rib by rotating a tool around the rib.

9. The method of manufacturing self-rolling umbrellas which comprises applying to an umbrella a cover longer in the direction of the rib than the distance between the points in the umbrella to which the cover is attached, securing a tip to the cover, applying a helical spring over the tip, placing the spring and tip over a rib on which the tip is rotatable, and winding up the spring on the rib by rotating a tool around the rib, which tool is inserted and removed laterally from said rib.

ARTHUR WRIGHT.
